CLAIM

The ornamental design for a monitor docking station having multiple docks for multiple tablet devices, as shown and described.

DESCRIPTION

FIG. 1 is a rear perspective view of a monitor docking station having multiple docks for multiple tablet devices; FIG. 2 is a front perspective view thereof;

FIG. 3 is a rear elevation view thereof;

FIG. 4 is a right elevation view thereof;

FIG. 5 is left elevation view thereof;

FIG. 6 is a top plan view thereof;

FIG. 7 is a bottom plan view thereof;

FIG. 8 is an alternate rear perspective view in a tilted orientation; and,

FIG. 9 is another alternate rear perspective view before the tablet is inserted into the docking station.

The broken lines showing tablets in the drawings illustrate environment that forms no part of the claimed design, while the remaining broken lines in the drawings illustrate portions of the monitor docking station having multiple docks for multiple tablet devices that form no part of the claimed design.
